UNITED STATES PATENT OFFICE.

CLARENCE W. YEITER, OF ALTO, MICHIGAN.

SNOWPLOW.

1,389,727.

Specification of Letters Patent. Patented Sept. 6, 1921.

Application filed March 29, 1920. Serial No. 369,767.

To all whom it may concern:

Be it known that I, CLARENCE W. YEITER, a citizen of the United States, residing at Alto, in the county of Kent and State of Michigan, have invented certain new and useful Improvements in Snowplows, of which the following is a specification.

My invention relates to improvements in snow plows for use upon automobiles, auto-10 trucks, and kindred vehicles, and its objects are: First, to provide a snow plow that may be readily attached to, or removed from an ordinary automobile or other kindred vehicle; second, to provide a snow plow with 15 which the snow may be taken from the highway front of the vehicle, and forced off to one side of the road, and, third, to provide a means whereby power generated in the vehicle may be utilized to force the snow, after 20 being accumulated in the crib of the plow, off to one side of the track being cleared of snow.

I attain these objects by the mechanism and arrangement of parts shown in the ac-25 companying drawing, in which Figure 1 is a front elevation of a part of an automobile with the crib of the snow plow shown in section to disclose the position and opera-30 tion of the sidewise conveying elements of the plow. Fig. 2 is an elevation of the front end of the right hand side of an automobile, showing the outlines of my devices in place, with the distributing fan in position. Fig. 3 is an elevation of the relatively left hand 35 side of an automobile with the near side wheels removed to enable me to show one means whereby the power generated in the automobile may be utilized for driving the snow conveying part of the plow.

40 Similar numerals indicate similar parts throughout the several views.

In the construction of this plow the first step consists in forming a crib, 5, in which a rotary spiral 4 is mounted to revolve freely. 45 I place an inclined shovel 10, having upwardly extending sides 17, by means of which the snow is forced upwardly and backwardly, as the automobile advances, and is deposited in the crib about the vertical center of the spiral 4 so there will be no danger of the snow becoming solidly packed in the crib before it is carried lengthwise thereof and is thrown off by the rapidly revolving fan 6.

55 To mount this plow upon the automobile,

I prefer the use of a strong supporting frame, as indicated at 16, which is properly secured to the frame of the automobile, 1, and the back of the crib should extend well upward, as at 2 to avert the danger of snow 60 being thrown upon the hood that covers the engine. In the accompanying drawing I have shown a sprocket wheel 9 connected with the spiral shaft, and a larger sprocket wheel 11 mounted upon the hind axletree 65 12, with a sprocket chain 14 connecting them to drive the spiral from the hind axletree, as one of the many available forms of connection that may be made for driving the spiral. 70

After the snow has been carried to the relatively right hand end of the crib 5 it is necessary to remove it as readily as possible, and for this purpose I have provided a rotary exhaust fan 6. To have this fan 75 work efficiently, it is desirable that it should revolve faster than the spiral does, and for this purpose I have shown it as mounted above the spiral shaft and as driven by a gear wheel 8 meshing with a gear wheel 7. 80 I have, also, shown this fan as standing at an inclined angle with the spiral shaft so it will have a tendency to force the snow upwardly as it leaves the crib 5, and well off of the line of plowing. 3 represents the 85 wheel fenders, 13 represents the front axletree, and 15 represents a supporting roller under the frame 16, which I find a very valuable adjunct to the plow as aiding to prevent the nose of the plow from being 90 forced solidly upon the ground when plowing very heavy snow. In this instance I have shown the spiral shaft as upon the same plane with the axletrees 12 and 13, but deem it well to place it as nearly the surface to 95 be cleared as is possible and not come too closely in contact with obstacles under the crib 5 or the incline 10.

It will be readily understood that a considerable deviation, both as to construction 100 and means of propulsion may be made in this device, without avoiding my invention.

What I claim as new in the art, is:

1. In a snow plow for use upon auto vehicles, a shovel mounted ahead of the vehicle and arranged to slide snow upwardly and backwardly as the vehicle advances, a crib mounted at the rear of the shovel laterally of the vehicle, a horizontally disposed revoluble spiral mounted longitudinally in 110

the crib, means for revolving the spiral from the power that propels the vehicle, a spiral exhaust fan mounted at the discharge end of the crib at an incline upwardly from the 5 longitudinal plane of the floor of the crib, and means for propelling said fan for exhausting snow from the crib and elevating it as it passes through the fan.

2. In a snow plow for use upon auto vehicles, a receiving crib, an inclined shovel for carrying snow into the crib as the ve-

hicle moves forward, a spiral mounted longitudinally in the crib, means for revolving said spiral to move the snow longitudinally of the crib, means for forcing the snow out 15 of the crib to one side of the vehicle and means for supporting the lower end of the shovel independently of its supporting frame, when moving heavy snow.

Signed at Alto, Michigan, March 25, 1920. 20

CLARENCE W. YEITER.
